DES. 2265

Thomas Devins of Cambridgeport Mass.
Letters Patent No. 3265 Dated Feb. 20. 1876
Design for a Coffin

The schedule referred to in these Letters Patent and making part of the same

To All whom it may concern:

Be it known that I, Thomas Devins of Cambridgeport in the County of Middlesex and

State of Massachusetts have originated and designed a new design for Coffins of which the annexed drawings are a full and exact representation.

Fig. 1st is a perspective view of the Coffin

Fig. 2nd is an end elevation

Fig. 3rd is a vertical section

Fig. 4th is a side elevation.

Claim

What I claim as my invention and desire to secure by Letters patent is the general configuration of the parts, as shown in the drawings, to form a new and original design for a Coffin.

Witnesses,

William Edson
